SYNTHESIS OF MOLYBDENUM AND
TUNGSTEN CARBONYLSDallas T. Hurd, Schenectady, N. Y., assignor to
General Electric Company, a corporation of
New YorkNo Drawing. Application June 6, 1950,
Serial No. 166,551

5 Claims. (Cl. 23—203)

1

The present invention relates to the synthesis of carbonyls of tungsten and molybdenum.

In accordance with a known method of preparing the carbonyl compounds of the heavier sixth group metals, molybdenum and tungsten, a chloride of the metal is reacted with carbon monoxide under pressure in the presence of a reducing metal. The reducing metals which have been employed heretofore for this purpose are zinc dust and iron dust, zinc dust being preferred for better yields.

The present invention is based on the discovery that certain new and unexpected improvements can be obtained by substituting granular aluminum for the known reducing metals, such as zinc dust. It has been found that finely-divided aluminum consistently gives higher over-all yields of the desired carbonyl than will zinc under reaction conditions which are otherwise similar. In addition, the reaction forming the carbonyl appears to proceed more rapidly with aluminum than with zinc or iron dust. A further advantage of the present invention is that the reaction mixtures employing aluminum are much easier to treat for the isolation of the carbonyl product than are those residues obtained employing zinc, for example, as the active metal. From the cost standpoint, aluminum is also preferable to zinc.

While in some cases the presence of a small amount of zinc dust may be found desirable for the purpose of initiating the carbonyl reaction, it is not essential for the actual reduction reaction and aluminum can be employed without it.

The term "aluminum reducing agent" as used herein is intended to include both metallic aluminum and aluminum-rich alloys. An example of a suitable alloy is one containing 50% copper, 45% aluminum and 5% zinc.

In order that those skilled in the art better may understand how the present invention can be carried into effect, the following illustrative examples are given.

Example 1.—Employing a closed reactor, 10 grams of tungsten hexachloride was reacted with 30 grams of 40-mesh zinc powder in 100 milliliters of anhydrous ether in the presence of 2500 lbs. per sq. in. of carbon monoxide for 16 hours at about 20° C. The product isolated by steam distillation of the reaction mixture comprised 3.6 grams of tungsten hexacarbonyl, representing a yield of approximately 41%.

Example 2.—Example 1 was repeated employing 15 grams of 30-mesh aluminum in place of the 30 grams of 40-mesh zinc powder. In addition, the pressure of carbon monoxide was lower,

being only 1500 lbs. per sq. in. The product from this reaction comprised 4.4 grams of tungsten hexacarbonyl, representing a yield of about 50%.

Example 3.—Example 1 was repeated substituting 15 grams of a powdered alloy of 50% copper, 45% aluminum and 5% zinc for the straight zinc. The yield was 5.3 grams of tungsten carbonyl, representing a yield of about 60% of the theoretical.

Example 4.—Employing a pressure reactor, 10 grams of tungsten hexachloride was reacted with 20 grams of 80-mesh zinc powder in 120 milliliters of ether under a pressure of 1500 lbs. per sq. in. carbon monoxide for 16 hours at 70° C. The yield of the reaction was 1.9 grams of tungsten carbonyl or about 21% of the theoretical.

Example 5.—Example 4 was repeated, substituting 15 grams of 60-mesh aluminum powder for the zinc powder and the reaction was carried out at room temperature. The yield was 5.7 grams of tungsten carbonyl or a yield of about 64% of the theoretical.

Example 6.—Example 4 was repeated employing the copper-aluminum-zinc alloy of Example 3 in place of the zinc. 15 grams of the powdered alloy was used. The reaction was carried out at a temperature of 100° for 3 hours and yielded 8 grams of tungsten carbonyl, representing a yield of about 90%.

Example 7.—Example 6 was repeated while maintaining the reaction at room temperature. The yield was 4.3 grams of tungsten carbonyl or about 49% of the theoretical.

Example 8.—Example 7 was repeated except that the pressure of carbon monoxide was 2500 lbs. per sq. in. instead of 1500 lbs. per sq. in. A yield of 4.7 grams of tungsten carbonyl represented about 53% of the theoretical.

From the above examples, it will be seen that aluminum and aluminum alloys consistently give better yields of the tungsten carbonyl than does the zinc. This is particularly true at the higher reaction temperatures of from 70 to 150° C. In this respect, the use of elevated temperatures is directly contrary to the general teachings of the prior art regarding the preparation of carbonyls employing reducing metals. While the amount of aluminum present in the reaction mixture has been found to have only a slight effect on the yield of the reaction provided that an amount sufficient to reduce the tungsten chloride is present, in general, the amount of aluminum by weight should ordinarily equal or exceed the weight of the tungsten or molybdenum hexachloride being reduced.

Molybdenum chloride can be substituted for tungsten chloride in any of the above examples with comparable results. With either molybdenum or tungsten chlorides, the reaction temperatures can range anywhere from room temperature to a maximum temperature of approximately 150° C. with temperatures somewhat above room temperature being preferred.

What I claim as new and desire to secure by Letters Patent of the United States is:

1. A process of preparing a metal carbonyl which comprises effecting reaction between carbon monoxide and a halide of a metal selected from the group consisting of tungsten and molybdenum in the presence of an aluminum reducing agent. 15
2. A process of preparing carbonyl which comprises reacting carbon monoxide with a chloride of a metal selected from the group consisting of tungsten and molybdenum and a finely divided reducing metal comprising aluminum. 20
3. The process of claim 2 in which the metal is an alloy of aluminum, copper and zinc.
4. The process of preparing tungsten carbonyl

which comprises reacting tungsten chloride with carbon monoxide under pressure and in the presence of aluminum.

5. The process of preparing tungsten carbonyl which comprises reacting tungsten chloride with carbon monoxide under pressure and in the presence of a substantial quantity of finely divided aluminum admixed with said chloride.
